Specification for Design.

Patented May 6, 1919.

Application filed December 1, 1916. Serial No. 134,536. Term of patent 14 years.

To all whom it may concern:

Be it known that I, GEORGE E. MESSINGER, a citizen of the United States, residing at Birmingham, in the county of Jefferson and State of Alabama, have invented a new, original, and ornamental Design for Vending-Machines, of which the following is a specification, reference being had to the accompanying drawing, forming part thereof.

Figure 1 a perspective from one corner, and Fig. 2 a like view from the other corner of the machine.

I claim:

The design for a vending machine, as shown.

Signed by me in the presence of two subscribing witnesses, this 23 day of November 1916.

GEORGE E. MESSINGER.
